UNITED STATES PATENT OFFICE.

JOHN C. RINGE, OF STRATFORD, CONNECTICUT, ASSIGNOR TO THE SINGER MANUFACTURING COMPANY, OF ELIZABETH, NEW JERSEY, A CORPORATION OF NEW JERSEY.

FEEDING MECHANISM FOR SEWING MACHINES.

Application filed February 25, 1925. Serial No. 11,407.

This invention relates to improvements in feeding mechanisms for sewing machines and more particularly in feeding mechanisms wherein a rotating feed-wheel is employed 5 to engage and advance the work.

An object of the present invention is to provide an improved feed-wheel actuating mechanism conveniently permitting changing the speed of rotation of the feed-wheel 10 to alter the stitch length of the seam produced by the machine. A further object of the invention is to provide a feeding mechanism which, while it may be quickly adjusted to vary the stitch length, is of such 15 a character as to prevent an unauthorized adjustment of said stitch length by the machine operator.

The present improvement is embodied in a continuous feed sewing machine, substantially as disclosed in the U. S. patent to H. Corral et al., No. 1,414,625, of May 2, 1922, wherein a work-advancing feed-wheel is continuously operated during the operation 25 of the machine and wherein the stitch-forming mechanism includes a reciprocating needle vibrated laterally in the direction of feed in timed relation with the advancing work.

The feed-wheel is carried by a shaft journaled in a frame which is pivotally supported upon a rotary actuating shaft carrying a series of driving gears in constant mesh with a series of driven gears loosely mounted upon the feed-wheel shaft. A selected driven gear is locked to the feed-wheel shaft by means of a detachable key, which is capable of being yieldingly held in position to lock only one particular gear and is replaceable by other keys each capable 35 of locking only one gear to the shaft. By placing the substitute gear locking keys in charge of someone who has authority to change the stitch-length when necessary, an operator is prevented from surreptitiously 40 changing the stitch-length desired for the work in hand, merely to increase production.

In the accompanying drawings, Fig. 1 is a longitudinal section of a sewing machine 50 embodying the present invention. Fig. 2 is a front end elevation, partly in section, of the same machine. Fig. 3 is a sectional view substantially on the line α — α of Fig. 2. Fig. 4 comprises perspective views of the detachable keys employed for locking the driven

gears to the feed-wheel shaft. Fig. 5 is a perspective view of the feed-wheel shaft knob, shown detached.

Referring to the drawings, the sewing machine shown is provided with a bed-plate 1, the upper surface of which serves as a cloth-plate. Rising from the bed-plate is the hollow standard 2 of the overhanging bracket-arm 3 terminating in the head 4. Suitably journaled in the arm 3 is the main or needle-reciprocating shaft 5 carrying at one end the belt-wheel 6 and at its opposite end the crank-disk 7, provided with the crank-pin 8. Embracing the crank-pin 8 is the apertured and laterally offset end of the link 9 70 of which the opposite end is connected in a like manner with the stud 10 projecting from the collar 11 suitably clamped upon the needle-bar 12.

The needle-bar 12 carries the needle 13 and is journaled for vertical reciprocation in spaced bearings, as 14, provided in the swinging frame 15 pivotally supported at its upper end upon the stud 16 secured in the head 4. In order to impart swinging movements to the frame 15 to positively vibrate the needle 13 in a direction to feed the work, the lower of the spaced bearings 14 is suitably connected with a crank-arm 17 on one end of the rock-shaft 18, journaled in bearings provided in the arm 3. The rock-shaft 18 is disposed substantially parallel to the driving shaft 5 and derives oscillatory movements therefrom by the provision of a forked arm 19 on said rock-shaft, which arm 19 is actuated by the eccentric 20, adjustable in any well known manner upon the shaft 5 to vary the throw of the arm 19.

Adjacent the eccentric 19, the driving shaft 5 carries the bevel-gear 21 meshing with the similar gear 22 carried by the upper end of the vertical, intermediate shaft 23 journaled at its upper end in a bearing provided in the lug 24 upon the standard 2. 95 Near its lower end, the shaft 23 is journaled in the bearing 25 formed in the frame of the housing 26 suitably secured to the bed-plate 1. Disposed within the housing 26 is the bevel-gear 27 and the worm 28 both carried by the vertical shaft 23. The bevel-gear 27 meshes with a similar gear 29 carried by the rearward end of the loop-taker actuating shaft 30 journaled in the bushing 31 suitably secured in the housing 26. The shaft 30 100 105 110

2

extends substantially parallel to the driving shaft 5 and is journaled at its forward end in the bushing 32 suitably secured in the loop-taker housing 33. Carried by the forward end of the shaft 30 within the housing 33 is the bevel-gear 34 meshing with the similar gear 35 suitably secured upon the vertical loop-taker carrying shaft 36 also journaled in the housing 33. The shaft 36 10 carries at its upper end a loop-taker 37 of a well known type containing a mass of under thread around which the needle-thread loops are cast in the usual manner to form lock-stitches. The bevel-gears 34, 35 are of a ratio whereby the loop-taker rotates twice for each rotation of the driving shaft 5.

The worm 28 upon the shaft 23 drives the worm-wheel 38 secured upon the substantially horizontal feed-wheel actuating shaft 20 39, journaled in suitable bearings provided in the housings 26 and 33 and functioning to drive the feed-wheel 40 projecting through a slot in the throat-plate 41 to engage and advance the work. A roller-presser 42 carried by the lower end of a presser-bar 43 is opposed to the feed-wheel 40, said presser-bar being journaled for endwise movement in the head 4 and being depressed in any suitable manner to cause the roller-presser 25 42 to yieldingly engage the work. The construction thus far described is substantially as disclosed in the prior Patent No. 1,414,625 hereinbefore referred to, the present invention residing more particularly in the means 30 employed for transmitting the rotary movement of the actuating shaft 39 to the feed-wheel 40 to continuously rotate the latter during the operation of the machine, at speeds which may be readily varied with 35 respect to the reciprocations of the needle.

A series of different size driving gears 44, 45 and 46 is secured upon the forward end of the shaft 39 by means of a fixed key 47 whereby said gears rotate in unison with the 40 shaft 39. These driving-gears are held against movement endwise of said shaft 39 in one direction by a screw 48 threaded into the end of the shaft 39 and in the other direction by a feed-wheel supporting frame 49 pivotally supported concentrically with the shaft 39 through the intermediary of a bushing 50 fixed in a suitable aperture provided in the housing 33 and constituting the bearing for the forward end of the shaft 39. 55

Journalized in a bearing aperture provided in the frame 49 is a shaft 51, upon the threaded reduced end 52 of which the feed-wheel 40 is secured by means of a nut 53, the feed-wheel rotating with said shaft 51. Loosely mounted upon the shaft 51 upon the side of the frame 49 opposite to that of the feed-wheel 40 is a series of different size driven gears 54, 55 and 56 separated by washers 57 which closely embrace the shaft 51. The driven gears are each provided

with a plurality of key-slots 58 preferably spaced approximately 120° around the shaft 51, said gears being held against movement endwise of the shaft 51 by means of a knob 59 secured by set-screws, as 60, upon said shaft 51. The knob 59 is partially cut away whereby the shaft-aperture 59' thereof merges into a key-slot 61 and whereby a key-head retaining shoulder 62 is provided adjacent said slot. The shaft 51 is formed with a slot 63 disposed longitudinally thereof, the inner end of the slot 63 preferably terminating in a curved wall 64. Fixed upon said wall 64, by means of a screw 65, is a bent spring 66, and intersecting the slot 63 70 at the end of the shaft 51 is a guide-pin 67. It is evident that while the driving gears 44, 45 and 46 are in constant mesh with the driven gears 54, 55 and 56, the feed-wheel is not driven upon rotation of the shaft 39 unless one of said driven gears is in some manner locked to the shaft 51 and that when one of said driven gears is locked to the shaft 51, the feed-wheel will rotate at a speed proportionate to the ratio of the driving and driven 75 gears selected. It is however desirable, in certain instances, that the means provided for locking any of the driven gears to the shaft 51 be of such a character as to prevent a machine operator from surreptitiously changing the speed of rotation of the feed-wheel, as for instance to increase production at a sacrifice of the stitch length desirable 80 for the work in hand. To this end, novel means has been provided for individually locking a selected driven gear to the shaft 51, said means comprising separate keys, as 68, 69 and 70, each provided with a flat upper face 71 from which projects a lug 72. The face 71 of each key terminates in a 85 shoulder 73 formed by the provision of an offset key-head 74, the shoulder 73 being preferably normal to the face 71. Each of the keys is beveled on its under side at opposite ends of the length thereof to provide a 90 restricted spring-engaging seat 75. The lugs 72 of the respective keys are spaced at different distances from the key-heads 74 as shown in Fig. 4, while the key-seats 75 are disposed at a substantially uniform distance 95 from the heads 74 and consequently the tendency of the bent spring 66 is to hold a key only in a position in which the lug 72 engages a key-slot 58 of the particular gear which said key is designed to lock to the 100 shaft 51. By placing the several keys in charge of someone having authority to change the stitch-length of the seam produced by operation of the machine, an operator is prevented from changing the stitch 105 length in an unauthorized manner. Nevertheless, whenever the occasion arises for changing the speed of rotation of the feed-wheel with respect to the needle reciprocations, it is only necessary for the authorized 110

115 120 125 130

person to remove a key from its operative position by bearing down upon the head 74 thereof and withdrawing it from the shaft-slot 63, whereupon the desired key may be inserted. The insertion of a key is facilitated by the provision of the guide-pin 66, upon which the lower edge of the key slides. The key is inserted the full length of the shaft-slot 63, in which position the key-seat 75 is in proper engagement with the spring 66 to cause the key-lug 72 to engage the key-slot 58 of the desired driven gear. Should the key-slot 58 be circumferentially out of alinement with the lug 72, the shaft 51 may 15 be turned relatively to the gear by means of the knob 59. The washers 57, together with the knob-shoulder 62, constitute dividing walls for the gear key-slots and insure against simultaneously locking two driven 20 gears to the shaft 51.

The frame 49, as previously stated, is pivotally supported upon the actuating shaft 39. The purpose of this construction is to permit adjustment of the level of the feed-wheel without impairing the intermeshing 25 relation of the driving and driven gears carried by the shafts 39 and 51. To effect adjustment of the feed-wheel level, i. e., to determine the degree of projection of the feed-wheel above the throat-plate 41, the frame 49 is provided at its free end 76 with a loosely journaled pin 77 into which is threaded an adjusting screw 78 which passes through an 30 aperture in the bed-plate 1 and of which the head 79 rests in a counter-sink formed in the upper side of said bed-plate. A spring 80 interposed between the bed-plate 1 and the pin 77 functions to maintain the screw-head seated upon the bed-plate. It is evident that 35 by adjusting the screw 78 the frame 49 may be raised or lowered at will.

The frame 49 affords a housing for the feed-wheel driving and driven gears by being provided with a lateral flange 81 constituting a support for a cover-plate 82 secured 40 by screws at 83 upon said flange. By reason of the fact that the actuating shaft 39 is constantly rotated during the operation of the machine, the feed-wheel is rotated to continuously 45 advance the work.

While in the present embodiment of the invention the driven gears are locked to the feed-wheel shaft 51, it is evident that the same result might be obtained by securing the driving gears in a similar manner to the shaft 39, and it is equally obvious that other changes and modifications may be made all 50 within the spirit of the invention and the scope of the appended claims.

Having thus set forth the nature of the invention, what I claim herein is—

1. A feeding mechanism for sewing machines comprising a rotary actuating shaft, a feed-wheel carrying shaft, constantly intermeshing driving and driven gears upon 60 said shafts, a detachable key for locking a selected gear to its shaft, and yielding means for maintaining said key in only one gear locking position.

2. A feed-wheel actuating mechanism for 70 sewing machines including a rotary shaft, a series of gears loosely mounted upon said shaft, means including a key effective to lock only one of said gears to said shaft, said key being replaceable by other keys each effective to lock one gear only to said shaft, and means for rotating the gear locked to the shaft to thereby rotate said feed-wheel to engage and advance the work.

3. A feed-wheel actuating mechanism for 80 sewing machines including a rotary shaft provided with a key-slot, a series of gears loosely mounted upon said shaft, a gear-locking key disposed in said shaft key-slot, yielding means for maintaining said key 85 within said shaft key-slot in only one gear locking position, and means for rotating the gear locked to the shaft.

4. A feed-wheel actuating mechanism for 90 sewing machines including a rotary shaft provided with a key-slot, a series of gears loosely mounted upon said shaft adapted to be selectively secured upon the shaft for rotation therewith, a spring disposed in said key-slot, a key disposed within said key-slot having a restricted spring-engaging seat whereby said key is maintained by said spring in only one gear-locking position, 95 said key being replaceable by others each effective to lock one gear only to said shaft, and means for rotating the gear locked to the shaft by a key.

5. A feed-wheel actuating mechanism for 100 sewing machines including a rotary feed-wheel carrying shaft provided with a key-slot, a spring disposed in said slot, a series of gears loosely mounted adjacent each other upon said shaft each provided with a key-slot, a key detachably disposed within the shaft key-slot having a lug entering a gear key-slot, said key being beveled on the side opposite said lug to provide a restricted spring engaging seat, means determining the gear-locking position of said key, and means 110 for rotating said gears.

In testimony whereof, I have signed my name to this specification.

JOHN C. RINGE.
